UNITED STATES PATENT OFFICE.

HARRY M. WILLIAMS AND JOHN W. DEAN, OF LITTLE ROCK, ARKANSAS.

WEED-DESTROYER.

1,238,861.

Specification of Letters Patent. Patented Sept. 4, 1917.

Application filed June 25, 1917. Serial No. 176,759.

To all whom it may concern:

Be it known that we, HARRY M. WILLIAMS and JOHN W. DEAN, citizens of the United States, residing at Little Rock, county of 5 Pulaski, and State of Arkansas, respectively, have invented certain new and useful Improvements in Weed-Destroyers, of which the following is a specification.

Our invention relates to weed killers and 10 particularly to devices especially adapted for destroying grass and weeds between and adjacent the right of way of a railway. Although the device is designed primarily as a weed killer, it is to be understood that 15 it is adapted for other uses such as removing ice, snow, etc., from rails, switches, frogs, etc.

The object of our invention is to provide 20 a device of the class mentioned, by means of which the weeds and grass may be quickly destroyed, or snow and ice readily removed without in any way injuring the rails, ties or other property. A further object of our 25 invention is to provide a device of the character mentioned, which will destroy the weeds at a considerable distance each side of the track and which will perform this function irrespective of the grade of the adjacent land, that is a device which will perform 30 this function equally well upon level ground or when the track is arranged upon fills or in cuts. Other objects will appear hereinafter.

With these objects in view, our invention 35 consists generally in a body supported upon wheels and equipped with means for projecting downwardly therefrom jets of superheated steam or superheated air. Our invention further consists in a device as mentioned in which the body is equipped with 40 lateral auxiliary portions or wings similarly equipped with superheated steam or air jets and means for adjusting the angular relation of the wings to the body portion so as to accommodate the same to the nature of 45 the ground adjacent the track, said auxiliary portion or wings being adapted to overlie the ground upon each side of the track. Our invention further consists in a device as 50 above mentioned equipped with means for raising and lowering the said body and wings with relation to the track. Our invention further consists in various details 55 of construction and arrangements of parts all as will be fully described hereinafter and particularly pointed out in the claims.

Our invention will be more readily understood by reference to the accompanying drawings forming a part of this specification and in which:

Figures 1 and 1^a are longitudinal, vertical, 60 sectional views illustrating one form of embodiment of our invention.

Fig. 2 is a similar view of a modified form of the invention. Fig. 3 is a plan view of the body and wings which together constitute 65 the burner.

Fig. 4 is a front elevation of the device illustrated in Fig. 1,

And Figs. 5 and 6 are a detailed cross section and bottom plan view respectively of a 70 portion of the burner.

In carrying out our invention the so-called burner, which comprises the above mentioned body and adjustable wings with the jets thereon, may be arranged upon an ordinary flat car and connected to a locomotive 75 as illustrated in Fig. 1; or the flat car supporting the burner may be equipped with its own motor power as illustrated in Fig. 2.

Referring now to the drawings, 1 indicates 80 a suitable wheeled device such as a flat car upon which the burner or weed and ice destroyer is arranged. Supported beneath the body of said flat car is the burner 2 which comprises a central body portion 3 85 and preferably equipped with laterally arranged wings or auxiliary portions 4 hingedly connected thereto as at 5. The portion 3 is connected to the body 1 by hangers 6, pivotally connected to both the portions 1 90 and 3, and suitable means are provided for swinging the burner upwardly when desired or found necessary. This preferably comprises a chain or other flexible member 7 connected at one end to the burner and at 95 the other end to a rotary member 8 upon which it is adapted to be wound, said rotary member being provided with means for actuating the same, such as a hand wheel 9, and also with means, such as a ratchet 10, 100 for holding the device in raised position.

The body portion 3, and each of the wings 4 preferably constitute imperforate plates and are provided on their under sides with transversely arranged pipes 11 which are 105 supplied through longitudinally disposed pipes 12 with a volume of superheated steam or superheated air, and said pipes 11 are provided on their under faces with apertures 13 forming jets for projecting the steam or 110

air downwardly. Swinging plates 14 are provided on the body 3, at the front and rear ends thereof which extend downwardly between the rails and upon the outside thereof, almost to the ties, and by means of which the heat is retained under the burner.

In order to adjust the angular position of the wings 4 chains 15 are connected thereto at one end, the other ends of the chains being connected to rotary member 16, similar to the member 8 and equipped with similar operating means 9 and ratchet devices 10.

As shown in Fig. 1, the steam is supplied to the burner from a locomotive 17 equipped with a superheater 18 connected through a pipe 19 and flexible connection 20 with a pipe 21 leading to the burner, the pipe 21 being connected to the longitudinally disposed pipes 12 through flexible connections

22. Preferably the pipe 21 is provided with a transverse section 21' which is connected by a plurality of flexible members 22, as shown clearly in Fig. 6. This arrangement provides for the free swinging of the wings 4.

In the form of the device shown in Figs. 2 and 3 the car 1 is provided with its own motive power comprising an engine 23 and a boiler 24 for supplying the steam thereto, as well as to the burner. In this form of the device the burner is of substantially the same construction and operation as in the form above described, with the exception that instead of flexible connection or hose 22 a pipe section 22' is substituted and connected at its ends by ball joints 25 with the pipe 21 and cross pipe 21" respectively. Steam is supplied to the superheater 18, from the steam dome 26 through a pipe 27 equipped with a valve 28.

Arranged upon the device is an air tank 29 connected through a pipe 30 with the pipe 27 between the valve 28 and the superheater 18. An air pump 31 is provided for maintaining air under pressure in the tank 29, through a pipe 32, and a valve 33 is arranged in said pipe. It is obvious that by closing the valve 28 and opening the valve 33 that steam will be cut off from the superheater but air will be supplied thereto and to the burner, so that with this form of the device either superheated air or superheated steam may be employed for destroying the weeds or melting the ice and snow from the track.

The operation of the device will be clear from the foregoing description and detail description thereof is superfluous.

We claim:

1. In a device of the class described, a body mounted upon wheels, means for projecting downwardly therefrom jets of fluid, and means for superheating said fluid before

reaching said projecting means, substantially as described.

2. A device of the class described comprising a body mounted upon wheels, laterally disposed portions hingedly connected thereto, said body and said lateral portions comprising imperforate plates, means on the under sides of said body and said laterally disposed portions for projecting jets of superheated fluid downwardly therefrom and means for adjusting said lateral portions angularly, substantially as described.

3. A device of the class described comprising a body mounted upon wheels, hingedly mounted depending plates arranged transversely thereof and means intermediate said plates for projecting jets of superheated fluid downwardly, substantially as described.

4. A device of the class described comprising a car, a body mounted thereon for vertical adjustment depending plates hingedly connected to said body and arranged transversely thereof to extend between the rails upon which the car travels and outside of said rails, to a point adjacent the ties, and means on said body for projecting downwardly a plurality of jets of superheated fluid, substantially as described.

5. A device of the class described comprising a body mounted upon wheels, a plurality of jets thereon for projecting downwardly a superheated fluid and means for supplying superheated steam or superheated air thereto as desired, substantially as described.

6. A device of the class described comprising a body mounted upon wheels a boiler and an air tank, a superheater, means on said body for projecting downwardly a plurality of jets of superheated fluid and means for connecting said boiler or said air tank to said superheater as desired, substantially as described.

7. A device of the class described comprising a body mounted upon wheels a boiler, means for propelling said wheeled body, an air tank, a superheater, means on said body for projecting jets of superheated fluid downwardly and means for connecting said boiler or said air tank to said superheater as desired, substantially as described.

In testimony whereof, we have signed our names to this specification in the presence of two subscribing witnesses.
